FLARE

Louis L. Driggs, Jr., Dayton, Ohio

Application March 20, 1936, Serial No. 69,781

10 Claims. (Cl. 102—24)

My invention relates to flares.

It is my object to provide a flare of the type that is supported by a parachute, that can be ejected from a rapidly-moving airplane without the opening of the parachute until the speed of the falling flare has been reduced after ejection from the plane to permit the parachute to safely open without being torn to pieces by reason of the velocity of the movement of the flare.

10 The problem that has arisen in connection with the ejection of flares that are supported by parachutes is this: Due to the increasing speeds of planes from which the flares are ejected, it is found that the parachutes will not stand the terrific speed when the flare is ejected into the slipstream of the plane, at the speed the plane is moving. It is not feasible to increase the size, weight, and strength of the parachutes.

It is the object of this invention to solve this problem by ejecting the flare and the parachute enclosed within a suitable casing as a unit with the parachute unopened; and thereafter, after the lapse of a predetermined time, due to the slowing down of the cylinder containing the flare and the parachute by reason of the air resistance the body of the cylinder sets up, the cover of the parachute is stripped from it and the parachute can open, and the flare is ignited.

It is an object to provide a hermetically sealed case for a flare and its parachute; and to provide an explosive means adapted to be ignited from a remote point in the plane, which explosive means will drive a casing containing the flare, its fuse, its ignition means and its parachute away from the plane as a unit. Thereafter the fuse serves to detach the casing around the parachute, so that it can open and serve to ignite the flare.

40 It is my object to provide a flare that will ignite only after it has left the plane and a fuse for igniting it that can only be initiated in its burning after the flare and fuse have left the plane a predetermined distance.

45 It is a further object to combine the function of the fuse for the dual purpose of igniting the flare and of stripping the cover from the parachute only after the lapse of a predetermined time sufficient to allow the flare and its parachute to reduce the speed below that at which it is travelling when ejected from the flare.

It is a further object to provide a separable casing for the flare and for the parachute and fuse control means for disconnecting these casings, so that the parachute can function.

It is an additional object to provide a hermetically sealed case to prevent the inlet of moisture into the case to injure the flare candle, parachute, explosive ejecting charge and fuse mechanism.

5 It is a further object to provide, optionally, a supplementary, small, very heavy and strong parachute which opens after the flare assembly has left the plane. Its purpose is to slow down the flare and to thereafter strip the casing or 10 container of the main parachute from the main parachute after that container has been detached from the container of the candle as a result of the action of the fuse. This supplementary parachute has an additional function, 15 which is an object of this invention, namely, that of lowering the main parachute container to the ground.

Referring to the drawings:

Figure 1 is a longitudinal section through the 20 flare casing, ejecting charge, fuse mechanism, candle and the casing around the parachute, showing the parachute as folded, and also showing the arrangement of the pilot parachute, which is optional.

25 Figure 2 is a side elevation of the flare assembly outside of its casing.

Figures 3 and 3a show an enlarged section of the flare in the projector tube and supported by the mounting bracket.

30 Figure 4 is a similar view showing the opening of the pilot parachute.

Figure 5 shows the stripping of the parachute container by the pilot parachute from the main 35 parachute just before the container is pulled away.

Figure 6 is a similar view with the container around the main parachute nearly removed, and with the flare ignited.

40 Figure 7 illustrates the pilot parachute lowering the main parachute container to the ground.

Figure 8 shows the flare, burning, being lowered to the ground by the parachute.

I have solved the problem which has arisen due to the high speed of airplanes, causing the 45 main parachutes to be ripped to pieces when they open after the ejection of the flare, by delaying the opening of the parachute until the ejected flare and parachute lose speed, due to the resistance of the body of the flare to the 50 air. I have solved this problem by ejecting the flare and the parachute unopened.

The cylinder containing the flare and the parachute moves away from the plane and loses speed until its speed has been reduced to a point 55

where it is safe to open the ordinary parachute.

At that point, the fuse in this cylinder, which has been ignited by the action of the ejecting charge, will have burnt through to a point where 5 the cap is blown off the cylinder. This cap is mounted over the end of the flare. Any means of ejection may be used.

The result of blowing off this cap is to pull 10 the strips that are connected to the locking pins. When the locking pins are pulled, the two halves of the spring retaining collar fall off the sleeves on the end of the flare and on 15 the end of the parachute container. This permits the flare which is connected to the main 15 parachute to pull the main parachute out of its cylindrical container, so that the flare, which is then ignited, can be supported in its descent towards the ground.

Supplementary to the foregoing is a small, 20 very strong pilot parachute, that is adapted to open shortly after the cylinder leaves the plane, but before the main parachute and the flare start functioning. This pilot parachute is very 25 strong and heavy. Its function is two-fold: First, to slow down the speed of the cylinder containing the flare and the main parachute, and, second, to insure the main parachute suitably opening. This pilot parachute cannot pull the main 30 parachute out of its casing until the collar is released, but it insures the removal of the cylindrical casing from the main parachute when the main parachute is detached from the flare by the 35 opening of the collar. The pilot parachute is connected only to the cylindrical casing containing the main parachute, so that the cylindrical casing will return to earth by itself supported by the small pilot parachute, and prevents this heavy casing from injuring anyone below.

Referring to the drawings in detail, I 40 designates a sheet metal support for supporting a flare casing on an airplane. The rubber collar 2 is interposed between the conical head 3 of the cap 4 and the plate 5 of the support 1. The cap 4 is retained in position by the bolts 6, carried 45 respectively by the cap 4 and the supporting plate 5.

The head of the conical cap 3 is provided with 50 an annular sleeve 7 that is internally threaded at 8. There is threaded into this sleeve the externally-threaded container 9, arranged as an inverted cup with an open bottom 10 closed by a disc 11. This cup contains the propelling explosive 12, having an igniter 13, which is connected by the wires 14 and 15 to the terminal 55 plug 16, that in turn is connected to an electric circuit, the energization of which is operated from the cockpit of the airplane.

The cap plate 4 is provided with an eye 17 that is bolted by the bolt 18 to the plate 4. 60 There is threaded through this eye the wire cable 19 to form a loop. The loop is retained in position by the clamp 20. This wire cable is connected to a coil of wire 21 at 22. The other end of the wire is connected to the loop 23 that is 65 mounted within a plate 24. This plate 24 is attached by nails or rivets 25 into the wooden block 26, which forms the fuse container. There is mounted in this removable plate 24 the ends 27 of the striking matches 28, the ends of which are 70 reversely bent as at 29 and carry a striking composition 30 thereon. Thus when they are drawn through the igniter composition 31, due to the pulling out of the plate 24 by the loop 23, the resulting flame ignites the powder 32 in the 75 capsules 33, which in turn ignites the fuse train

34. This fuse train is used to ignite the material designated 36. This results in stripping the cap 37 containing the fuse block 26 and fuse mechanism from the end of the flare 38 and results in igniting the flare. It will be understood 5 that the initiation of this ignition of the fuse by the striking of the wire 29 and its composition 30 upon the material 31 does not take place until the cable 21 is stretched its full length, at which time the flare and its parachute are completely outside of the flare casing 38.

The cap 37 has its upper end, at 37a, turned 10 inwardly and then up and over a ring 37b, which is carried on the inside of the casing 39 at its top. 15

It will be further understood that the bottom of this casing 39 is hermetically sealed by the cap 40. The cap 40 has a flange 41, with an arcuate rib 42, overlapping an extended portion 43 on the casing 39. Between these two portions 20 is a resilient ring 44. When the flare and its 25 parachute with its casings is driven out as a unit from the casing 39, this cap 40 is stripped from the casing 39. The flare and its parachute are driven out due to the explosive force of the explosive material 12.

Means to detach the flare casing and the parachute casing

The lower end of the cap 37 is provided with 30 a band 45. Threaded through this band through an eye therein as at 46 on either side of the band is a strap 47. The end of the strap is threaded through the eye and turned over and riveted as at 48. This flat metal strap extends down to the 35 bottom of the flare 38, where it enters an eye 49 in a pin 50. This pin is the pin retaining the ends of the halves of the locking ring together. These ends overlap and have eyes at 51 for receiving the pin 50, and when the pin 50 is pulled 40 out, the halves fall apart so as to release the connected casings for the flare designated 52 and for the main parachute designated 53.

These locking plate halves which are preferably semi-circular and are split spring bands, 45 carry inwardly-projecting studs 54 that engage with corresponding apertures in the annular collars 55 and 56 which are respectively mounted on the adjacent ends of the casings 52 and 53. These collars 55 and 56 have turned-over flanges 50 abutting one another at 57. The collar 55 is mounted upon an end plate 58 at the bottom of the flare casing 52. The collar 56 is mounted on the end of the parachute casing 53 by suitable rivets 59. 55

Thus when the pins 51 are pulled, the split spring bands constituting the locking plate spring apart, removing the studs 54 from the apertures in the collars 55 and 56, permitting those collars to separate. 60

Parachute removal

The main parachute which is shown in folded condition at 66, has connected to its usual ropes 61 the cable 62, the other end of which is 65 anchored in an eye 63 mounted in the end plate 66 of the flare casing. This cable is used to support the flare with its burning end downwardly when the parachute opens.

It will be observed that the straps 47 which 70 pull the pins 51 do so when the fuse ignites the flare, and causes a stripping of the flare end from the cap 37, so that simultaneously the casing of the flare and the casing of the main 75 parachute will be separated, so that the main

parachute can then be pulled from its casing and opened to support the flare with its burning end downwardly.

Due to the fact that the flare casing and the 5 parachute casing have been joined together as a single instrumentality, when they are ejected as a unit forcibly from the flare casing 39, this 10 unit structure tumbles over and over while the fuse is burning, and during this period the 15 whole structure slows down materially from that speed which it had attained with the plane when it was ejected from the plane. The speed therefore is reduced to a safe point before the spring locking plates are permitted to separate by pulling the pins 51, due to the operation of the 20 fuse. Therefore, the main parachute will not be pulled out of its casing 53 until the speed of the flare has slowed down to a point where the 25 parachute will not be ripped to pieces by the excessive speed of the air to which it is being subjected.

Pilot parachute

Under some conditions it is desirable to supplement the relatively light-weight, large, main 25 parachute by a pilot parachute, designated 64, which is mounted in a separate compartment 65 in the end of the main parachute casing 53 and at the bottom thereof. This small pilot 30 parachute is made of very heavy material and is extremely strong. It is held in position by the cap 40 of the main flare casing, but it immediately opens upon the main parachute and the 35 flare being ejected by the force of the explosive 12 from the main casing 39, which results in stripping of the sealing cap 40. The pilot parachute 64 is connected by a cable 66 to the head 40 of the main parachute casing 53.

Therefore, its first function is to resist the 40 movement of the composite flare casing and main 45 parachute casing, which have not yet been detached from one another because the fuse has not yet burnt through to a point where the cap 31 is stripped from the flare and the straps 41 are pulled. Thus, the small parachute 64 serves to reduce the speed of this composite cylinder just as soon as it leaves the plane.

Thereafter the second function of the pilot 50 parachute takes place. When the fuse operates to bring about the detachment of the main 55 parachute case 53 from the flare case 52, the pilot parachute pulls the main parachute case 53 away from the main parachute 60 so that it is stripped therefrom, permitting the main 60 parachute to open quickly and easily, but at a time 65 and at a speed which is entirely safe for the main parachute.

Then the pilot parachute 64 enters upon its 65 third function. This function is to slowly and safely lower the heavy case 53 of the main 70 parachute, so that it will not be injured, so that it will not injure anything on the ground, and so that it is more easily located.

Method of operation

With this description of the details of operation of this flare, the sequence of operations can 75 be understood by referring particularly to Figures 4 to 8 inclusive, where the successive stages of the operation of the parts can be seen diagrammatically illustrated.

In Figure 4 the parts are illustrated in that position which they occupy after the composite cylinders, comprising the casings 52 and 53 with the unopened main parachute 60 and the flare, 80 have been ejected by the explosive 12 from the

casing 39 after stripping the hermetically sealed cover 40. The cable 21 is stripped to its full length and is just about to initiate the burning of the fuse 34. The cap 37 is still in place. If the pilot parachute is being used, it will now 85 start to leave its receptacle and open, as indicated. It cannot yet pull the main parachute casing 53 away because it is attached by the 90 spring locking plates or collars to the flare casing 52.

In Figure 5 the parts are shown in that position in which the cap 37 with the straps 47 have now been blown away by the explosive 36, resulting in pulling the pins 51 and permitting the 95 spring locking plate halves to spring apart so that the casings 52 and 53 can separate. The main parachute 60 is just beginning to emerge, due to the lengthening of its cable 62, and due to the fact that the pilot parachute is now pulling the main flare casing 53 away from the main 100 parachute. The flare candle has been ignited and is now burning.

In Figure 6 is shown the parts with the main 105 parachute container or casing 53 nearly pulled away from the main parachute 60.

Figure 7 shows the pilot parachute supporting 110 the main parachute container or casing 53 on its way to the ground.

Figure 8 shows the main parachute opened 115 and supporting the burning flare as it descends 120 towards the ground.

It will be understood that I desire to comprehend within my invention such modifications as may be necessary to adapt it to varying conditions and uses.

Having thus fully described my invention, what 125 I claim as new and desire to secure by Letters Patent, is:

1. In combination, a flare candle, a support for 130 said flare candle, a parachute connected to said candle, a casing for the parachute detachably connected to the flare candle, a fuse mounted on the flare candle, igniter means adjacent said fuse, means connecting said igniter means to the support for said candle for operating the igniter 135 means when the candle has moved a predetermined distance away from said support; and an explosive means mounted on said candle ignitable by said fuse and adapted to blow away said fuse from the candle and ignite the candle; and means 140 connected to said fuse for detaching the parachute casing from the flare candle to permit the 145 parachute to open.

2. In combination, a flare candle, a casing 150 therefor, a parachute connected to said casing, a 155 parachute casing, means for detachably attaching said candle casing and said parachute casing in abutting relationship, said attaching means comprising interlocking spring collars engaging 160 said respective casings, pin means for connecting 165 said collars, a strap means connected to said pin means and a fuse cap on the end of the candle and connected to said strap, whereby when the 170 fuse cap is removed the pin means permits the 175 spring retaining collars to detach the candle and 180 parachute casings, so that the parachute can 185 open and support the candle.

3. In combination, a flare candle, a casing 190 therefor, a parachute connected to said casing, a 195 parachute casing, means for detachably attaching 200 said candle casing and parachute casing in abutting relationship, said attaching means comprising interlocking spring collars engaging 205 said respective casings, pin means for connecting 210 said collars, a strap means connected to said pin 215 means,

means extending to adjacent the end of the candle and a fuse cap connected thereto on the end of the candle, whereby when the fuse cap is removed the pin means permit the spring retaining collars to detach the candle and parachute casings, so that the parachute can open and support the candle, and an explosive means located between the end of the candle and the fuse cap, ignitable by the fuse and adapted to blow away the fuse cap, ignite the candle and operate the pin means to detach the flare and parachute casings.

4. In combination, a candle and a casing, a parachute connected to the casing for support of the candle, a parachute casing detachably connected to the candle casing in abutting relationship, overlapping spring collars having interengaging studs in said respective casings, pin means for retaining said spring collars in operative position, a strap connected to said pin means, a cap on the end of the candle and having said strap attached thereto, a fuse in said cap, explosive means between the cap and the end of the candle, whereby when the fuse ignites the explosive means the cap is blown off, the pin means is pulled with the strap and the parachute casing is detached from the candle casing to permit the opening of the parachute.

5. In combination, a candle and a casing, a parachute connected to the casing for support of the candle, a parachute casing detachably connected to the candle casing in abutting relationship, overlapping spring collars having interengaging studs in said respective casings, pin means for retaining said spring collars in operative position, a strap connected to said pin means, a cap on the end of the candle and having said strap attached thereto, a fuse in said cap, explosive means between the cap and the end of the candle, whereby when the fuse ignites the explosive means the cap is blown off, the pin means is pulled with the strap and the parachute casing is detached from the candle casing to permit the opening of the parachute, a support for said foregoing assembly, a cable connected to said support at one end and to the fuse at the other end, and means to explosively drive the assembly away from the support, so that upon the extension of the cable the fuse will be ignited by the pull of the cable.

6. In combination, a candle and a casing, a parachute connected to the casing for support of the candle, a parachute casing detachably connected to the candle casing in abutting relationship, overlapping spring collars having interengaging studs in said respective casings, pin means for retaining said spring collars in operative position, a strap connected to said pin means, a cap on the end of the candle and attached to said strap, a fuse in said cap, explosive means between the cap and the end of the candle, whereby when the fuse ignites the explosive means the cap is blown off, the pin means is pulled with the strap and the parachute is detached from the candle casing to permit the opening of the parachute, a support for said foregoing assembly, a cable connected to said support at one end and to the fuse at the other end, means to project the assembly away from the support, so that upon the extension of the cable the fuse will be ignited by the pull of the

cable, and a sealed casing for retaining said assembly until ejected from the casing by said projecting means.

7. In combination, a candle and a casing, a parachute connected to the casing of the candle, a parachute casing detachably connected to the candle casing in abutting relationship, overlapping spring collars having interengaging studs in said respective casings, pin means for retaining said spring collars in operative position, a strap connected to said pin means, a cap on the end of the candle and attached to said strap, a fuse in said cap, explosive means between the cap and the end of the candle, whereby when the fuse ignites the explosive means the cap is blown off, the pin means is pulled with the strap and the parachute casing is detached from the candle casing to permit the opening of the parachute, a support for said foregoing assembly, a cable connected to said support at one end and to the fuse at the other end, means to explosively drive the assembly away from the support, so that upon the extension of the cable the fuse will be ignited by the pull of the cable, and a sealed casing for retaining said assembly until ejected from the casing by said explosive means, and means for remotely igniting said explosive means electrically.

8. In combination, a support casing; a flare candle, a main parachute connected thereto, a main parachute casing directly detachably connected to said flare candle, a pilot parachute connected to said main parachute casing and contained between the end of the parachute casing and the support casing; means on said flare candle comprising a fuse, a fuse cap and an explosive means adapted upon ejection from the support casing of the flare candle and the main parachute casing with the pilot parachute to detach the main parachute casing from the flare candle, so that the pilot parachute can open and strip the main parachute casing from the flare candle, and means for ejecting said pilot parachute, main parachute casing and flare candle with its fuse from said casing, and means connected to the support casing and to said fuse for initiating the igniting of the fuse after the flare candle has moved a predetermined distance away from said support casing.

9. In combination, a flare candle, a fuse cap mounted thereon at one end, a parachute casing mounted thereon at the opposite end, a parachute in said casing attached to said flare candle, an explosive cap removing means interposed between the candle and the fuse cap, and means connected to the cap for detaching the parachute casing from the candle upon removal of said cap by said explosive means.

10. In combination, a flare candle, a fuse cap mounted thereon at one end, explosive cap removing means interposed between the candle and the cap, a parachute casing detachably mounted on said candle at the other end, a parachute in said casing and attached to said flare candle, and means connected to the cap for detaching said parachute casing from the candle upon removal of the cap by said explosive means, and means in said cap for igniting the fuse, said means being adapted to operate upon exertion thereon of a predetermined pull.

LOUIS L. DRIGGS, JR.
